DESIGN FOR A BOTTLE

Harry D. Henshel, New York, N. Y., assignor to Bardstown Distillery, Inc., Bardstown, Ky., a corporation of Delaware

Application October 19, 1937, Serial No. 72,300

Term of patent 14 years

To all whom it may concern:

Be it known that I, Harry D. Henshel, a citizen of the United States, residing in New York city, in the county of New York and State of New York,
have invented a new, original, and ornamental Design for a Bottle, of which the following is a specification, reference being had to the accompanying drawing, forming part thereof.

Fig. 1 is a front view of a bottle showing my new design;

Fig. 2 is a side view of the same; and

Fig. 3 is a top plan, transverse sectional view taken on line 3—3 of Fig. 1.

I claim:

The ornamental design for a bottle as shown.

HARRY D. HENSHEL.
